DESIGN FOR A DISPENSER FOR POPCORN
OR THE LIKEJohn S. Francis, Los Angeles, Calif., assignor to Frank P. Emerson, Los Angeles, Calif.

Application May 4, 1940, Serial No. 92,161

Term of patent 3½ years

To all whom it may concern:

Be it known that I, John S. Francis, a citizen of the United States and residing at Los Angeles, in the county of Los Angeles and State of California, have invented a new, original, and ornamental Design for a Dispenser for Popcorn or the like, of which the following is a specification, reference being had to the accompanying drawing, forming part thereof, in which:

Fig. 1 is a front elevational view of a dispenser for popcorn or the like showing my new design;

Fig. 2 is a side elevational view thereof showing a movable part thereof in a closed position;

Fig. 3 is a side elevational view thereof showing the movable part in an open position.

I claim:

The ornamental design for a dispenser for popcorn or the like, as shown.

JOHN S. FRANCIS.
